United States Patent

Des. 238,926
Patented Feb. 24, 1976

238,926

SPANNER WRENCH

Azel Thad Wall, Rte. 3, Box 37, Greensboro, N.C. 28310

Filed Jan. 21, 1975, Ser. No. 542,706

Term of patent 14 years

Int. Cl. D8—05

U.S. Cl. D8—27

FIG. 1 is a front perspective view of a spanner wrench embodying my invention;

FIG. 2 is a front elevational view of FIG. 1;

FIG. 3 is a left side elevational view of FIG. 2;

FIG. 4 is a top plan view of FIG. 3; and

FIG. 5 is a bottom plan view of FIG. 2.

I claim:

The ornamental design for a spanner wrench, as shown.
